UNITED STATES PATENT OFFICE.

ERNEST LA FONTAINE PROVOST, OF QUINONES, CUBA.

COLLAPSIBLE WARDROBE.

Application filed April 15, 1927. Serial No. 184,096.

This invention relates to storage devices, particularly to wardrobes, and has for its object the provision of a novel wardrobe which may be quickly and easily set up for use to form an enclosure within which garments of various kinds may be stored, or which may be just as easily collapsed into a small and compact bundle convenient for transportation or storage.

10 An important object of the invention is to provide a device of this character which is particularly well adapted for use by traveling people and also by campers and others, the device being preferably constructed of 15 water-proof material of a flexible nature so as to constitute adequate protection for the garments hung therein.

Another object of the invention is to provide a device of this character which embodies only two rigid frame members which are themselves foldable and provided with novel means for maintaining them in extended position when in use, an advantage of this construction being extreme lightness in 25 weight.

Another object is to provide a device of this character provided with pockets adapted to contain insecticide whereby the device will be of particular advantage for use in the 30 tropics where insect life is very abundant.

Additional objects are to provide a device of this character which will be simple and inexpensive in manufacture, easy to set up and use, or knocked down for transportation, positive in action, efficient and durable 35 in service, and a general improvement in the art.

With the above and other objects and advantages in view, the invention preferably 40 consists in the details of construction and the arrangement and combination of parts to be hereinafter more fully described and claimed, and illustrated in the accompanying drawings, in which:

45 Figure 1 is a perspective view of the complete device showing it set up ready for use.

Figure 2 is a vertical sectional view therethrough.

50 Figure 3 is a vertical cross sectional view taken on the line 3—3 of Figure 2.

Figure 4 is a horizontal cross section taken on the line 4—4 of Figure 2.

Figure 5 is a perspective view of the device folded or collapsed into compact form.

55 Figure 6 is a detail section taken on the line 6—6 of Figure 1, and

Figure 7 is a detail perspective view of the bottom frame member.

Referring more particularly to the drawings, I have shown the device as comprising 60 similar upper and lower frame members 10 and 11, each of which is here shown as including a pair of sections 12 hingedly connected at 13, these sections being preferably 65 of slat like form though obviously this is not necessary as it is conceivable that they could be solid if preferred for any reason. The hinges 13 are located at the bottom of the sections so that when they are supported at the ends, the hinges will act to prevent the 70 sections from folding together or onto one another.

In addition to these top and bottom frame members, the device includes a flexible casting designated as a whole by the numeral 14 75 and including a back portion 15, sides 16 and a front 17 as well as a top 18 and bottom 19. Canvas, oil-cloth or other similar material may be employed for the purpose of forming these elements and it is of course 80 preferable that the material be water-proof especially if the device be intended for use out of doors or in a very damp climate. The back, sides, top and bottom may be made of different pieces secured together or of one 85 continuous piece cut to the proper shape, which ever is preferred, and these elements are continuous whereas the front 17 is cut away in order to provide an opening which is adapted to be closed by means of a curtain 90 20 which may be stitched or otherwise secured at one edge and suspended at its top by loops 22 or the like and which is provided at its bottom and at its other edge with snap fasteners or the like 23 by means of 95 which it may be fastened down to form a complete closure for the front of the device. Obviously, there are no restrictions as to the 100 particular type of snap fastener used, as it is clearly apparent that turn-buttons could be 105 employed with equal advantage.

Another feature is the provision of a plurality of fabric or other suitable pockets 24 located on the inside of the fabric covering or wall and designed for the purpose of 110 holding insecticide or material, chemicals or the like which are repulsive to insects so that any garment stored within the device will be protected from the ravages of moths or other insects.

As an additional feature, either or both of the sides 16 may be provided with pockets

25 within which may be stored handkerchiefs, socks or other small articles such as collars, neckties and the like. These pockets may or may not be provided with closure flaps; this detail being immaterial.

It is also intended that means be provided for suspending coats, suits, dresses or the like within the device and in carrying out this feature, I may provide a plurality 10 of screw eyes 26 depending from the intermediate slats of the top frame member 12, these screw eyes serving as supporting means for hangers 27 which may be constructed from wire or any other material 15 and which may be of any ordinary or preferred type or of special design as preferred by the manufacturer.

It is intended that the device be suspended when in use and for this reason I have disclosed 20 wooden or other blocks 28 adapted to be fastened to a wall, tree or the like, these blocks carrying hooks 29 and 30, the latter of which are engaged by screw eyes 31 carried by the rearmost slat of the top frame member 10. The hooks 29 are adapted to be engaged by rings or the like 32 forming part of or connected with chains 33 which are threaded through screw eyes or the like 34 carried by the top frame member 10, and 25 which are connected with other screw eyes 35 mounted at the forward edge of the top frame member. It will be apparent that when the chains 33 are threaded through the screw eyes 34 and connected with the screw eyes 35, the top frame member, and consequently the entire device will be adequately supported, the hooks 30 really serving simply to steady the entire structure in its suspended position.

40 In the use of the device, it is of course apparent that garments of any and all descriptions may be hung therein and other articles be stored within the pockets 25. Clearly, the garments will be protected from 45 injury by light, insects, dust, dirt, moisture and the like, and will be kept in proper condition ready for service at any time. When use of the device is not desired, it is readily apparent that it may be detached from the 50 suspension means and be folded into compact form as clearly illustrated in Figure 5 of the drawings, so as to occupy the minimum space in transportation or storage.

From the foregoing description and a 55 study of the drawings, it will be readily apparent that I have thus provided a very simply constructed, inexpensive and highly efficient device for the purpose specified and one which will perform all functions for 60 which it is intended. It is really believed that the construction, operation and advantages will be readily apparent to one skilled in the art without further explanation.

While I have shown and described the preferred embodiment of the invention, it

should be understood that I reserve the right to make such changes in the form, construction, and arrangement of parts as will not depart from the spirit of the invention or the scope of the subjoined claims.

Having thus described the invention, I claim:—

1. A device of the character described comprising top and bottom frame members, a closure connected with said frame members and formed of flexible material, the closure having an opening in its front provided with a movably mounted curtain for closing the same, and suspension means for the device including attaching members, suspension elements mounted on the attaching members, flexible members detachably engaged upon the suspension elements, and guides carried by the top frame member and through certain of which said flexible members are threaded and with certain others of which the flexible members are detachably connected.

2. A device of the character described comprising top and bottom frame members each formed of a pair of sections hingedly connected at the bottom, a closure connected with said frame members and formed of flexible material, the closure including a back wall, sides, a top, a bottom, and a front portion having an opening therein, and a movably mounted curtain for closing the open portion of the front, and suspension means for the device including attaching members, suspension elements mounted on the attaching members, chains detachably engaged upon the suspension elements, and guides carried by the hinged sections of the top frame member and through certain of which said chains are threaded and with certain others of which the chains are detachably connected.

3. A device of the character described comprising top and bottom frame members each formed of a pair of sections hingedly connected at the bottom, a closure connected with said frame members and formed of flexible material, the closure including a back wall, sides, a top, a bottom, and a front portion having an opening therein, and a movably mounted curtain for closing the open portion of the front, and suspension means for the device including attaching members, suspension hooks mounted on the attaching members, chains detachably engaged upon the suspension members, and screw eyes carried by the hinged sections of the top frame member and through certain of which said chains are threaded and with certain others of which the chains are detachably connected, the entire device being adapted to be folded into compact form when not in use.
